CARL H. WOLFF, OF ST. LOUIS, MISSOURI, ASSIGNOR TO WAGNER ELECTRIC CORPORATION, OF ST. LOUIS, MISSOURI, A CORPORATION OF DELAWARE.

SHORT-CIRCUITING MECHANISM.

Application filed January 16, 1924. Serial No. 686,505.

My invention relates to a circuit changing mechanism and one of its important applications is for the reorganizing of the winding circuits of an alternating current motor through the agency of centrifugal mechanism, a specific application being for the purpose of short-circuiting the windings of a single phase repulsion motor to automatically convert it at the desired speed into an induction 10 motor.

Among the objects of my invention are to produce a unitary device for the purpose mentioned, which will occupy small space and thus require very little enlargement of the over- 15 all dimensions of the machine, and one which may be adjusted to operate at the desired speed before attaching it to the motor. Other objects and advantages of my invention will appear from the following more detailed de- 20 scription.

In the accompanying drawings Figure 1 is a front view of a short-circuiting mechanism embodying my invention; Figure 2 is a rear view; Figure 3 is a side view; and Figure 4 is 25 a view partly in elevation and partly in cross section, showing the mechanism applied to a motor.

In the form illustrated in the drawings my improved circuit-closing mechanism comprises a supporting plate 1 secured to a collar 2, which makes a press fit with the motor shaft 3. At the opposite ends of the supporting plate are formed ears 4 and 5 which form bearings for the pivot pins 6 and 7. On 35 these pivot pins weighted members 8 and 9 are mounted, these members comprising U-shaped pieces, to each of which is attached semi-circular weights 10 and 11, each being in the form of half of an annulus and ar- 40 ranged to partially embrace the motor shaft. Springs 12 tend to hold the weighted members in retracted position. The weights and spring tension are so proportioned that the weights will move outwardly under the influence 45 of the centrifugal force developed at the desired speed. In Figure 4 the weights are shown in their retracted position, and Figures 1 and 3 illustrate the position of the parts in the circuit-closing position.

Mounted on the free ends of the centrifugal members is a circuit-closing disk 13 having a central opening for the passage of the rotor shaft. The disk is provided with slots as shown, through which pass the headed pins 55 14 carried by the centrifugal members. Spac-

ing pieces 16 between the weights and the disk permit the desired relative motions of these parts without interference. The circuit-closing mechanism is mounted adjacent to the commutator 15, which is provided with 60 a vertical face to be engaged by the resilient contact pieces formed by slitting the periphery of the short-circuiting disk 13.

As shown in the drawings, the pivot points of the centrifugal members 8 and 9 are spaced 65 away from the motor shaft and are located at a greater distance from the shaft than the point of connection between these members and the short-circuiting disk 13. The arc of outward motion of the centrifugal members 70 is therefore so located that the movement of these members from retracted position will impart to the disk a motion longitudinal of the rotor shaft and thereby bring this disk into contact with the ends of the commutator 75 segments when the predetermined critical speed has been attained. It will be understood that the motor is started and brought up to speed by means of current supplied to the brushes 17 which cooperate with the horizontal surface of the commutator. 80

The inward movement of the weights, under the influence of the springs, is limited by the slots in the disk in cooperation with the headed pins 14 and the disk is thus resiliently 85 but firmly held against any tilting movement and prevented from coming into contact with the commutator except under desired conditions. Simplicity of construction and small number of parts is attained in the arrangement described by the fact that the centrifugal members constitute the sole supporting 90 means for the disk and actuate it in the desired direction without the use of means for changing the direction of motion. 95

Having fully described my invention, what I claim as new and desire to secure by Letters Patent of the United States is:

1. Circuit changing mechanism comprising a pivoted centrifugal member, and a circuit-closing member supported by the centrifugal member by means of a pin and slot connection. 100

2. Circuit changing mechanism comprising a pair of pivoted centrifugal members, a circuit-closing disk mounted thereon, and connections between each centrifugal member and the disk permitting limited relative motion between said members and disk. 105

3. Circuit changing mechanism comprising 110

ing a pair of pivoted centrifugal members, a circuit-closing member carried by said centrifugal members, and means on the centrifugal members and firmly engaging the 5 circuit-closing member when the centrifugal members are in retracted position to prevent tilting of the circuit-closing member.

4. Circuit changing mechanism comprising, the combination of a centrifugal member, a circuit-closing member mounted on the centrifugal member by connecting means permitting limited relative motion between said parts, the relative positions of the pivot points of the centrifugal member and its 10 point of connection with the circuit-closing member being such that movement of the centrifugal member from retracted position imparts longitudinal movement to the circuit-closing member.

20 5. Circuit changing mechanism comprising the combination with a rotatable shaft, of a support mounted for rotation with the shaft, centrifugal members pivoted to said support on opposite sides of said shaft, and 25 a circuit-closing disk mounted on said centrifugal members.

6. Circuit changing mechanism comprising the combination with a rotatable shaft, of a support mounted for rotation with the 30 shaft, centrifugal members pivoted to said support on opposite sides of said shaft, and a circuit-closing member supported on the centrifugal members by means of pin and slot connections.

35 7. Circuit changing mechanism comprising the combination with a rotatable shaft,

of a support mounted for rotation with the shaft, centrifugal members pivoted to said support on opposite sides of said shaft, and a circuit-closing disk carried by said centrifugal members by means of pin and slot connections, said connections being arranged to limit the motion of the free ends of the centrifugal members toward each other. 40

8. Circuit changing mechanism comprising the combination with a rotatable shaft, of a support mounted for rotation with the shaft, centrifugal members pivoted to said support on opposite sides of said shaft, a circuit-closing disk carried by said centrifugal members by means of pin and slot connections, said connections being arranged to limit the motion of the centrifugal members toward each other, and means tending to 45 impel said members toward the shaft. 50

9. Circuit changing mechanism comprising the combination with a rotatable shaft, of a supporting member mounted on the shaft for rotation therewith, centrifugal members pivotally carried by said supporting member and having their free ends closely adjacent to the shaft when in retracted position, means tending to hold said members in said retracted position, and a circuit-closing member carried by the free ends of said centrifugal members, the pivot points of the centrifugal members being at a greater distance from the shaft than the free ends of said members when in retracted position. 55

In testimony whereof, I have hereunto set 70
my hand this the 12th day of January, 1924.

CARL H. WOLFF.
